E. F. Driggs

United States Patent Office.

IMPROVED SASH-HOLDER AND FASTENER.

E. F. DRIGGS, OF BROOKLYN, NEW YORK.

Letters Patent No. 60,156, dated December 4, 1866.

SPECIFICATION.

TO ALL WHOM IT MAY CONCERN:

Be it known that I, ELLIOTT F. DRIGGS, of Brooklyn, in the county of Kings, and State of New York, have invented a new and useful improvement in Sash-Holders and Fasteners; and I do hereby declare the following to be a full, clear, and exact description thereof, reference being had to the accompanying drawings, figures, and letters of reference thereon, making part of this specification.

The drawing shows a front elevation of a window with my invention attached thereto.

The object of my invention is to hold the window sash securely at any desired height, and also securely lock the same when the window is closed; and consists in the employment, in combination with a window sash, of a ratchet-bar and a spring pawl or catch, as will be fully explained hereafter.

To enable others skilled in the art to make and use my invention, I will describe the construction and operation thereof.

A represents the window sash, the edge of which is grooved to receive a metal ratchet-bar, C, which is secured to the window casing, B, the casing in the drawing being broken away to show the internal arrangement. The teeth on the ratchet-bar all point upwards except the lower one, a, which points in the reverse direction. To the window sash I secure a spring pawl or dog, b D, and a thumb-piece, E, as plainly shown.

The operation will be as follows: To raise the window the thumb-piece, E, is pressed to the right, which withdraws the dog D from the ratchet-tooth, a, and the window raised to the desired height; the dog D then catches on a ratchet-tooth and holds it securely. To lower the window the dog is withdrawn from the teeth, and when the window is down the dog passes under the inverted ratchet-tooth, a, and securely locks the window.

I am aware that metallic ratchets have been combined with windows to support the sash, an example of which may be seen in patent No. 12,833, but I am not aware of any instance in which a ratchet has been used having teeth pointing up and down, whereby the window sash may be supported in any desired position and locked.

I claim, in combination with a window sash A, a ratchet C, provided with teeth as described, and a spring dog or pawl D, provided with a thumb-piece E, the whole constructed and operating substantially as described and specified.

E. F. DRIGGS.
